MITRE BOX

William J. Hildebrandt, West Simsbury, and Richard H. Russell, Farmington, Conn., assignors to The Stanley Works, New Britain, Conn.

Filed Nov. 27, 1974, Ser. No. 527,542

Term of patent 14 years

Int. Cl. D8—05

U.S. Cl. D8—71

FIG. 1

FIG. 2

FIG. 3

FIG.4

FIG.5

FIG.6

FIG. 1 is a perspective view of a mitre box showing our new design;

FIG. 2 is a plan view thereof;

FIG. 3 is a bottom view thereof;

FIG. 4 is a front elevational view thereof;

FIG. 5 is a rear elevational view thereof; and

FIG. 6 is a side elevational view thereof, the opposite side elevational view being a mirror image thereof.

We claim:

The ornamental design for a mitre box, as shown and described.
